UNITED STATES PATENT OFFICE.

ISRAEL GREENBERG, OF LOS ANGELES, CALIFORNIA.

MACHINE FOR MANUFACTURING ROOFING TILE.

Application filed November 29, 1926. Serial No. 151,513.

This invention relates to a machine for manufacturing roofing tile or other similar articles that are adapted to be formed in molds; and an object of the invention is to provide a machine that is easy to operate and effective in operating.

To that end I provide a machine having side receptacles or hoppers at the sides thereof that are accessible to an operator so that both the mold plates and also the material are easily within reach; and also the machine is so constructed and arranged that it can be operated to produce tile and the like of a superior quality.

Another object is to provide a machine for forming tile and the like with a means connected thereto for evenly distributing coloring matter over a face of each tile so that when glazed and finished all the tile will be substantially alike as to color. That is the even and uniform distribution of color on the tile permits them to be uniform in color and not blotched and inharmonious in appearance.

Another object of the invention is to provide a simple means for lifting the mold plates out of the molds when the tiles are formed. This means includes a foot lever for each mold which can be actuated by an operator's foot so that both his hands are free to receive the tile charged mold plates when they are lifted from the mold.

Another object of the invention is to provide a machine for forming tile that is easy to construct and assemble and which is strong and durable in use.

A feature of the invention is shown in the novel means employed for forming and polishing the top surface or face of the tile and trimming the edges thereof.

Another feature of the invention is shown in the means employed for cleaning the tops of the molds and returning the excess material to the hopper to be used again so that waste of material is avoided.

Other objects, advantages and features of invention may appear from the accompanying drawings, the subjoined detailed description and the appended claims.

The accompanying drawings illustrate the invention, it being understood that many of the parts in nearly all the figures are shown semi-diagrammatically.

Figure 1 is a front view of a machine that is constructed in accordance with this invention; showing by dotted lines an altered po-

sition of the edge cutter and groove forming parts.

Fig. 2 is a view from the right hand side of the machine.

Fig. 3 is a plan view of the machine showing a tile formed in one of the molds and the other mold empty to show the adjustable support for the mold plate, and means for elevating it.

Fig. 4 is an enlarged plan view of the color spreader showing the revolving hopper partly in section.

Fig. 5 is a side view of the color spreader.

Fig. 6 is a perspective view of one form of tile that is adapted to be formed by the machine.

Fig. 7 is a fragmental cross section through the machine showing in detail the general formation of the molds and tile, and also showing a side view of the hand bar for shaping and glazing the tile.

Fig. 8 is a view of the underside of the hand bar shown in Fig. 7.

Fig. 9 is a combined side and edge view of a tamper used to form a flange at the end of each tile.

Fig. 10 is a combined edge and side view of a trowel for shaping and glazing the flange formed on the end of each tile.

Fig. 11 is a combined edge and side view of a tamper used to tamp down the material into the molds.

The main frame of the machine includes the legs 15, cross plates 16, 17, braces 18 and T irons 19; and on opposite sides of this frame and secured thereto is an oil tank 20 for holding the tile molds and a hopper 21 for holding the tile forming material that are supported and braced by bars 22.

Two rectangular molds 23 and 24 are supported on the top of the frame and the tops and bottoms of these molds are open.

Cross plates 25 are secured to the bottoms of these molds and these plates carry the adjustable screws 26, four in number for each mold, that are adapted to support the mold plates 27 in the bottoms of the molds in level or horizontal position.

The plates 27 are fitted snugly to the inner walls of the mold so that when filled with tile they can be moved upward out of the mold into a position in which they can be removed from the ejector by hand.

There are two mold ejectors; each includes a spider 28 secured to a pair of vertical bars 29, slidable through a guide plate

30. The spiders 28 are adapted to evenly engage the undersides of the mold plates 27 and hold them substantially in level or horizontal position while being ejected from 5 the molds.

The bars 29 are actuated by foot treadle levers 31 that are pivotally connected to bearings 32 on a front cross bar 16. These levers are extended between the bars 29 and 10 are arranged to extend under and engage rollers 33 pivotally mounted between the bars. The purpose of the rollers 33 is to prevent excessive friction between the moving parts when the ejectors are actuated.

15. The mold plates are formed with an upper surface comprising alternate ridges and recesses that correspond to similar ridges and recesses in a top surfacing bar 34, it being understood that the surfacing bar and molds 20 are spaced apart a sufficient distance for the tiles 35 to be formed between them.

The ridges and recesses are offset relative to one another and are arranged so that at opposite sides of each tile there is an overlap 36 that is adapted to be fitted to and rest on an under extension 37 of another tile when the tiles are in use.

The surfacing bar 34 is provided with two pairs of rollers 38 adjacent its ends that are 30 adapted to ride on the top edges of the T irons 19 when the bar is in use to form and glaze the upper surface of the tile, and these rollers are best shown in Figs. 7 and 8. The bearings 39 for the rollers 38 are 35 extended so that they engage the sides of the vertical flanges of the T irons 19 to guide the bar 34 when it is forced backward and forward over the face of the tile to shape and glaze it.

40. Spring scrapers 40 are secured to the bar 34 by screws 41 and the purpose of these scrapers is to engage the top side edges of the molds 23, 24 and keep them clean when the machine is in use.

45. A chute 42 is arranged under the molds 23, 24 to carry the excess material back to the hopper 21.

The foregoing described parts of the machine are adapted to form the bodies of the 50 tile; that is the mold plates 27 can be placed in and supported in the molds 23 and 24 which are then filled by hand from the hopper 21. After the molds are filled a tamper 43 shown in Fig. 11 is used to tamp the 55 material until it is evenly settled. Then the bar 34 is placed on the T irons 19 adjacent their forward ends and operated forward and backward to form the top surface of the tile and remove any excess material therefrom, which, as previously stated, is returned by the chute 42 to the hopper.

60. Then the top surface of the tile is covered by a coloring material and the means for applying the color comprises a revolving cylindrical sieve 44 that is supported in a

movable frame 45 that is adapted to be moved into and out of position over the mold boxes 23 and 24.

The frame 45 is provided with a front shaft 46 that is rotated by a crank 47. A 70 pair of spools 48 is mounted on this shaft in alignment with similar spools 49 mounted on a loose shaft 50 that is normally forced away from the shaft 46 by a pair of springs 51.

75. The sieve 44 has closed ends with spindles 52 that carry spools 53 that are aligned with the spools on the shafts 46 and 50. The spools are connected by a pair of straps 54 that extend over the pairs of pulleys 48 and 49 and wind once around the intermediate pair of pulleys 53 so that when the shaft 46 is rotated away from the shaft 50 the sieve will be rolled toward the shaft 46 and when rotated in the opposite direction the 85 sieve will also be rolled in the opposite direction; and as the sieve is rotated it will cause the powdered coloring matter therein to sift evenly out of the sieve and onto the top 90 surface of the tile.

90. Normally the sieve is arranged to rest over a hopper 55 that catches any of the material falling out of the sieve when it is not being operated to color the tile. It is filled with color through a trap door 75.

95. The frame 45 is pivotally connected by a toggle arm 56 to a post 57 secured to one corner of the main frame of the machine, and the pivoted toggle connection permits the movable frame and sieve to be moved off to the side of the machine or arranged directly over the molds 23 and 24 so that in use no coloring matter falls off of the tile to be wasted.

100. When the sieve is arranged over the filled molds it can be rotated by the crank 47 to move backward and forward over the tile until they are sufficiently and evenly covered with the coloring matter; and then it can be moved off to the side of the machine as described. Preferably cylindrical agitators 58 are arranged inside the sieve to aid in the 110 discharge of coloring matter therefrom when the appliance is in use.

115. After the coloring matter is placed on the tile it is polished by means of the hand bar 34 which is placed on the T irons 19 and operated as previously described; that is, it is moved backward and forward until the 120 top surface of the tile is glazed.

125. A means is provided for forming an end flange to the tile. Three parallel bars 59, 60 and 61 have their rear ends pivotally connected to a bearing plate 62, and they are arranged so that they trim the side edges of the tile formed in the molds 23 and 24 when in use and raised from the molds. The forward ends of these bars are connected to a die plate 63 that has recesses 64 that are adapted to register with the forward ends 130

of the tile when the end flanges are being formed. Pivots connected to the bars 59, 61 are short bars 65, 66 that have a straight edge 67 secured to their forward end that coats with the die plate 63 in forming dies in which the end flanges of the tile can be molded.

When the parts 63 and 67 are in full line position shown in Figs. 1, 2 and 3 the recesses 64 can be filled with the plastic material to form end flanges 68 to the tile. A hand operated tamper 69 shown in side and end elevation in Fig. 9 is used to tamp the material into the recesses 64. After these recesses are filled and tamped a finishing trowel 76 shown in side and end elevation in Fig. 10 is used to glaze the upper surface of the flange 68.

When not in use the plate 63 and straight edge 67 and associated bars can be turned back to the dotted position shown in Figs. 1 and 2, where they incline against a support 71.

In use a large number of mold plates 27 are stored in the open top oil filled tank 20 accessible to an operator. A plate is placed in each of the molds which are then filled with plastic material and finished as described. Then the tile filled plates are ejected from the machine by the foot treadles and removed from the spiders to a drying rack. Then other oiled plates are placed in the molds and the tile forming process continued.

The detailed construction and operation of the revolving sieve and associated parts will be covered in a separate application for a United States Letters Patent.

What I claim as my invention is:

1. In a tile machine the combination of a frame, a pair of mold boxes supported by said frame, tile molds for closing the bottom of said mold boxes and shaping the bottom surface of the tile formed on said molds; an oil tank offset from said frame

for holding said tile molds, a hopper offset from said frame for holding tile forming material, and a hand bar adapted to shape and glaze the upper surface of the tile, said bar having guides, spring scrapers and rollers thereon for the purpose specified.

2. In a tile machine the combination of a main frame, a mold box supported by said frame, means for forming a tile in said mold box, another frame, a pivotal connection between said frame; a rotary cylindrical sieve supported by said other frame and arranged to be moved toward or from said mold box, and means for rotating and reciprocating said sieve when arranged over said mold box for the purpose specified.

3. In a tile machine, the combination of a main frame, a mold box supported by said frame, means for forming a tile in said mold box, another frame pivotally connected to said main frame, a rotary cylindrical sieve supported by said other frame, means for reciprocating said sieve backwards and forward when arranged over the mold box; and a false hopper supported by said other frame over which said sieve is normally arranged when not in use.

4. The elements set forth in claim 3, and cylindrical agitators within said sieve that coat therewith when said sieve is in use; and a center door through which coloring matter is supplied to said sieve.

5. In a tile machine, the combination of a frame; a mold box supported by said frame, means connected with said box for forming the body and lower surface of a tile, a hand bar shaping and glazing the upper surface of a tile while in said box, guides adjacent the ends of said bar, pairs of rollers arranged between said guides, and spring scrapers secured to said bar for the purpose specified.

In witness whereof, I have hereunto affixed my signature.

ISRAEL GREENBERG.
